CASING FOR A CIGARETTE LIGHTER

Charles K. Lovejoy, Atlanta, and Frank H. Stephens, Jr., Dunwoody, Ga., assignors to Scripto, Inc., a corporation
of Georgia

Filed Sept. 27, 1965, Ser. No. 87,195

Term of patent 14 years

(Cl. D48—27)

FIG. 1 is a view in side elevation of a decorative surface treatment for a casing for a cigarette lighter showing our new design; and,

FIG. 2 is a top plan view thereof.

The dominant features of our design reside in the portions shown in full lines.

We claim:

The ornamental design for a casing for a cigarette lighter, substantially as shown and described.
